CIRCULAR KNITTING MACHINE

Percival Arthur Bentley, Charles Frederick Manger, Carlyle Herbert Wainwright, and George Alfred Buswell, Leicester, England

Application July 1, 1931, Serial No. 548,174,
and in Great Britain July 4, 1930

6 Claims. (Cl. 66—136)

This invention is for improvements in or relating to circular knitting machines.

In the U. S. patent to Bentley et al. 1,769,662, granted July 1, 1930, there is described a yarn-feeding mechanism comprising a unitary yarn-feeding device (indicated at 12 in Figure 1 of the drawings of said specification) which is movable into and out of yarn-feeding position in the machine and which has two yarn-guiding passages. These two passages are so spaced relatively that when the device is at the knitting location of the machine the yarn issuing from one of said passages has imparted to it the necessary lead over the yarn issuing from the other passage so as to ensure that one yarn is knitted into the work over the other as a plating yarn.

The present invention provides yarn-feeding mechanism of the kind described in the said prior patent wherein a unitary yarn-feeding device of the kind above mentioned is adapted to feed yarns to the needles during reciprocatory knitting and yet to maintain unaltered the relative positions of the two yarns when knitted into the work.

The invention, accordingly, comprises yarn-feeding mechanism of the type above mentioned wherein the unitary yarn-feeding device has a yarn-guiding passage in a form (for instance that of a slot), providing spaced guiding surfaces, one or the other of which surfaces acts as a yarn-guide according to the direction in which reciprocatory knitting is being performed, and has another yarn-guiding passage disposed substantially midway between the spaced surfaces of the first-named passage.

The present invention also provides yarn-feeding mechanism of the kind described in the said prior patent wherein the unitary yarn-feeding device has provision for adjustment between its two yarn-guiding passages.

The above and other features of the invention, all particularly pointed out in the appended claims, will now be described in connection with several constructions, illustrated somewhat diagrammatically in the accompanying drawings, which serve as illustrative examples of the invention.

In the drawings:—

Figure 1 is a plan of one of said constructions;

Figure 2 is a plan of another of said constructions;

Figure 3 is an elevation of the feeder mechanism shown in Figure 2, as regarded from the interior of the needle cylinders;

Figure 4 is a plan of a third construction of feeder mechanism;

Figures 5 and 6 are views, taken at right-angles to one another, of a clamp device of the mechanism of Figure 4;

Figures 7, 8 and 9 are details hereinafter referred to;

Figure 10 is a diagrammatic view of the parts adjacent the yarn-feeding location of the machine and shows, inter alia, the relative positions of the two yarn passages of the feeder of Figure 2 and of the latch guard carried by said feeder during the yarn-feeding operation by said feeder; and

Figure 11 is a section on the line 11—11 of Figure 10.

The accompanying drawings illustrate only so much of the yarn-feeding mechanism and other parts of the machine as will enable the present invention to be understood, it being assumed that the mechanism for operating the yarn-feeding devices and the construction and operation of other parts of the machine, except as hereinafter mentioned, are substantially the same as those described in the patent to Bentley et al. hereinbefore referred to.

All of the yarn-feeding devices illustrated in the drawings are of the "unitary" type mentioned in the said prior patent, that is to say, they comprise two yarn-guiding passages so spaced apart that yarn issuing from one passage will be knitted, in the operation of the machine, over the yarn issuing from the other passage, as is the case in plated work. The yarn-feeding devices illustrated may be regarded as of two different kinds of which one (see for instance the device 20 of Figure 1) is adapted to supply two yarns to the needles during rotary knitting, while the other kind (see for instance the device 22 of Figure 1) is adapted to supply two yarns to the needles not only during rotary knitting but also during reciprocatory knitting in such manner that during both of these conditions of the machine one and the same yarn is always knitted over the other. For the sake of conciseness, the kind of feeder exemplified by the device 20 (Figure 1) will be referred to hereinafter as a rotary-knitting feeder while the kind exemplified by the device 22 (Figure 1) will be termed a reciprocatory-knitting feeder.

Referring first to Figure 1, the mechanism shown therein comprises a pair of yarn feeders in the form of levers 20, 22 pivoted at 24 to a plate 26 supported on a post 28 projecting upwardly from a stationary part of the machine. These feeders are moved into and out of yarn-feeding position about their pivot 24 in the

manner described in the said prior patent, the feeder 22 being shown in yarn-feeding position in Figure 1, in which the position of the needle cylinders is indicated at 30. The feeder 20 is 5 a rotary-knitting feeder and is substantially the same as the feeder 12 of the said prior specification, its spaced yarn-guiding passages being indicated at 19, 21. The feeder 22, however, is a reciprocatory-knitting feeder, one of the yarn-guiding passages therein being in the form of a slot 32 over which is situated the other passage 34, which is circular in cross-section, at a position substantially midway between the ends 10 of the slot 32. When the feeder 22 is in operative position, as in Figure 1, yarn is fed to the needles by way of the passages 32, 34, the yarn guided by an end of the slot 32 being given the necessary lead over the other yarn issuing from the hole 34 owing to the relative disposition of said slot-end and hole, as will be appreciated by those skilled in the art. When the direction of rotation of the machine is periodically reversed, as in reciprocatory knitting, each end of the slot 32 in turn will serve as the yarn-guiding surfaces, thus maintaining the lead of one yarn over the other, irrespective of the direction of rotation 15 of the machine.

The construction shown in Figures 2 and 3 comprises a reciprocatory-knitting feeder 22 as described in connection with Figure 1, and a rotary-knitting feeder 36. The feeder 36 in this construction has provision for adjustment between its yarn guiding passages 35, 37 in a direction substantially height-wise or longitudinally of the needle cylinders. For this purpose, the inner end of the lever constituting the feeder is slit at 38 lengthwise of the lever into two portions 40, 42 each of which has formed in it one of the passages 35, 37, the slit being of sufficient length as to permit the portions 40, 42 to be sprung relatively. In the specification of said Letters Patent there is described mechanism (see Figure 3 of the drawings of said prior patent), 20 including a plunger 110 and a rocking arm 114, which are employed to move the feeder 12 of that specification upwardly against the action of a spring 112 to a given level in the machine when that feeder is at the knitting location. In the present construction, a rocking arm 48, with an attached pin 46, corresponding to the said arm 114 and plunger 110, is arranged to engage by said pin 46 the portion 42 of the lever 36, the portion 40 of said lever being prevented from moving with, or from partaking of the full movement of, the portion 42 when that portion is lifted by the rocking arm against the action of a spring 43 which corresponds to the spring 112 of said prior specification. For this purpose the portion 40 is provided with a downwardly-extending stem 50 which passes through an arc-shaped slot 52 (concentric with the pivot 24) in a plate 54 secured to the underside of the plate 26 and which has threaded upon it, below the plate 54, a nut 56 and lock nut 58. When the lever 36 25 is moved upwardly by the action of the rocking arm 48 and pin 46, the nut 56 on the stem 50 engages the plate 54 and prevents the portion 40 from moving upwardly with the portion 42, with the result that when the latter arrives at its proper level at the knitting location, the two portions 40, 42 will have been separated to an extent that gives between the two passages 35, 37 an adjustment, heightwise of the needle cylinders, which is found to give the best results in 30 the knitting. By varying the position of the

80 nuts 56, 58, on the stem 50, the degree of separation of the two portions 40, 42 of the feeder lever 36 can obviously be varied.

The machine to which the present construction is applied may be provided with a latch guard 60, Figures 10 and 11, somewhat similar in shape to the plate 110^x shown in Figure 14 of the drawings accompanying the specification of British Letters Patent No. 247,334 and comprising an inverted V-shaped recess 62 similar to the recess 106^x of said plate 110^x. When the yarn feeder 85 constituted by the lower lever 36 is swung into yarn-feeding position, it is liable to strike the latches of the needles as the latches pass across the lower part of said recess. To prevent this from happening means is provided, in accordance with this invention, for closing the lower part of said recess. This means may comprise an arc-shaped arm 64 carried by, or formed integral with, the yarn feeder 36 which is constituted by the lower of the said two levers, the centre of curvature of the inner edge of said arm being coincident with the axis of the pivot 24 about which the yarn-feeder 36 swings in its movements between operative and inoperative positions.

90 It will be understood that the arc-shaped arm 95 by reason of its shape and disposition on the feeder presents to the lower part of the inverted V-shaped recess aforesaid, a latch-guarding portion at all times, that is to say, not only when the feeder is moving into its operative position but also when it is in its inoperative position. It 100 will be noted that in the construction under consideration the latch guard 64 is carried by, or formed integral with, the portion 42 of the feed lever 36 which is acted upon by the rocking arm 48 and pin 46 before mentioned. The guard 64, when the feeder 36 is in feeding position, will thus be raised relatively to the portion 40, and to prevent the latches from striking against the portion 40 and being damaged thereby, the corner of this portion is bevelled off at 66, as shown in Figures 3 and 10. Figures 10 and 11 are illustrative of the action of the latch guard 64, the path 110 of the needle latches as the needles move to the 115 position in which they take the yarns 68 from the feeder, being indicated at 70 in Figure 10.

120 In the construction illustrated in Figure 4, there are, as in the two constructions already described, 125 two yarn feeders of which the lower one is a rotary-knitting feeder and the upper one a reciprocatory-knitting feeder. The lower feeder 72 is similar to the feeder 20 of Figure 1 but is provided with a latch guard 74 similar to and functioning in a similar manner to the latch guard 64 of Figures 2 and 3. The upper feeder 76, in this construction, has provision for adjustment between its two yarn-guiding passages 78, 80. The passage 78 is constituted by a slot which, like the constructions already described, is in a member 130 formed on, or secured to, the inner end of the feed lever, but the passage 80 is formed in a part that is adjustably supported on the feed lever. This part is constituted by a rod or wire 82 which is adjustably secured to the upper side of the lever 76 at a point between the inner end of the lever and the pivot 24 about which the lever can swing. The passage 80 is formed near one end of the rod 82 and this end of the rod is bent at 135 an angle to the remaining part or shank of the rod, the angle being such that when the rod is secured in adjusted position on the lever 76 the axis of the yarn-guiding passage 80 extends more or less lengthwise of the lever. The rod 82 is 140 145 150

secured to the lever 76 by a split clamp 84 and a screw 86, the shank of the rod 82 being engaged in a hole 88 (Figures 5 and 6) in the sleeve-like part of the clamp and the screw, passing through 5 clearance holes 90 in the two flanges of the clamp, being threaded into a hole in the lever 76.

By the arrangement just described, when the screw 86 is loosened, the position of the yarn-guiding passage 80 in relation to the lever 76 can 10 be adjusted by sliding the rod 82 in the clamp 84, by turning the rod in the clamp, thus raising or lowering the bent part of the rod in which the passage 80 is situated, and by moving both rod and clamp about the axis of the screw 86. 15 The adjusted position of the passage 80 is then maintained by tightening the screw 86, the tightening of which causes the rod 82 to be gripped by the clamp and the clamp to be secured to the lever. Thus the passage can be adjusted in three mutually perpendicular directions whereby its relation 20 to the slotted passage 78 and its relation to the needle circle—when the lever is in yarn-feeding position—can be determined to a nicety, an advantage in certain classes of work, such for 25 instance, as broad rib fabric.

Usually, the slot in a feeding device according to this invention is straight in formation as is indicated in Figure 7 which is a diagrammatic end view of the feeder 22 of Figure 1, and in Figure 9 which is a similar view of the feeder 76 of Figure 4, but in certain circumstances a curved slot may be advantageous. An instance of this is shown in Figure 8 which is a diagrammatic end view of a feeder provided with a slot 132 curved upwardly at its ends towards the level of the companion yarn passage 134, which latter may be adjustable in relation to the slot 132, for instance as in the construction of Figure 4.

It is deemed desirable here to point out that 40 the terms "slot" and "circular in cross-section" applied herein to the yarn-guiding passages of the feeders, are intended as terms of identification and not of limitation, as other configurations of a feeder enabling one yarn to be fed from substantially a single point (e. g. the passage 34) and 45 another yarn from two spaced points (e. g. the ends of the slot 32) are considered to be within the scope of the present invention.

Although in the constructions herein illustrated, 50 each of the two yarn feeders of each construction is adapted to feed two yarns to the needles, one of said feeders, for instance the feeder 20 or 72 of Figures 1 and 4, respectively, may be adapted, as is the feeder 10 of said prior patent to Bentley et al., to feed but a single yarn. It is preferred, 55 however, to employ the feeders illustrated as an arrangement whereby each feeder can deliver two yarns and is advantageous in that a greater variety of work can be performed by the machine, for instance, different parts of the work may be 60 plated, if desired with yarn from either of the feeders. Furthermore, more than two feeders may be employed, if the nature of the work to be knitted calls for such an arrangement.

65 It will be noted that three different kinds of yarn-feeding devices are referred to herein, viz., a device providing a single yarn-guiding passage applicable for both rotary and reciprocatory knitting; a device providing two spaced passages, 70 applicable (when both passages are supplied with yarn) for rotary knitting; and a device providing a passage having two spaced guiding surfaces and also providing a further and separate passage situated between such surfaces, especially appli-

cable for reciprocatory knitting, but also applicable for rotary knitting. It will, therefore, be appreciated that even if a machine be provided with but two feeders, one of each of said kinds, large variety of work may be produced, which variety will increase with the number of feeders employed. 80

We claim:

1. In a circular knitting machine, yarn-feeding mechanism comprising a yarn-feeding device having two relatively-adjustable portions, two yarn-guiding surfaces on one of said portions which are spaced apart to serve alternatively as yarn-guides, a yarn guide on the other of said portions disposed substantially midway between said spaced surfaces, and a support upon which said device is mounted for movement between a yarn-feeding position and an idle position. 85

2. In a circular knitting machine, yarn-feeding mechanism according to claim No. 1, wherein the two portions of the yarn-feeding device are relatively adjustable in three mutually perpendicular directions. 90 95

3. In a circular knitting machine, yarn-feeding mechanism comprising a support, a lever, a pivotal connection between said support and lever, said lever being divided into two portions by a division extending from an end of the lever towards said pivotal connection, a yarn guide at the free end of each of said portions, and means to spring said 100 portions relatively, to effect adjustment between 105 said yarn guides. 100

4. In a circular knitting machine, yarn-feeding mechanism comprising a support, a pivot carried thereon, a lever mounted on said pivot and arranged to yield lengthwise thereof, said lever being divided into two portions by a division extending from an end of the lever towards said pivot, a yarn guide at the free end of each of said 110 portions, means adapted to engage one of said portions and tending to move the lever lengthwise of its pivot, and an adjustable device adapted to prevent movement of the other of said portions under the action of the said means, whereby on actuation of said means the said two portions 120 of the lever are sprung relatively to a degree controlled by said adjustable device, to effect adjustment between said yarn guides. 115 120

5. In a circular knitting machine, yarn-feeding mechanism comprising a support, a lever pivoted 125 thereon, yarn-guiding surfaces on said lever which are spaced apart to serve alternatively as yarn guides, a member constituted by two angularly disposed portions, a yarn guide on one of said portions, and an adjustable connection between 130 said other portion and the lever, said adjustable connection permitting said member to be turned and moved endwise in said connection, and to swing with said connection on said lever, whereby the relative position of said yarn guides can be 135 adjusted. 130

6. In a circular knitting machine employing needle cylinders, yarn feeding mechanism comprising a yarn feeding device having two portions relatively adjustable longitudinally of the needle 140 cylinders, a yarn guide on each of said portions, and a support upon which said device is movably mounted as a unit between a yarn feeding position and an idling position. 145
